UNITED STATES PATENT OFFICE.

ALFRED MUNRO COURTNEY PRATT, OF HOBART, TASMANIA, AUSTRALIA, ASSIGNOR
TO WILLIAM GEORGE ASHLIN, OF HOBART, TASMANIA, AUSTRALIA.

COOKING STOVE.

Application filed March 21, 1922. Serial No. 545,558.

To all whom it may concern:

Be it known that I, ALFRED MUNRO COURTNEY PRATT, a subject of the King of Great Britain, residing at 117 Harrington 5 Street, Hobart, State of Tasmania, Australia, have invented certain new and useful Improvements in and Connected with Cooking Stoves, of which the following is a specification.

10 This invention relates to the construction of cooking stoves and has principally for its object the cleansing of the flues in a self-acting way. This is effected by mechanisms hereinafter to be described operating mainly 15 from the movement of a sliding oven door. Further, by sliding the fire box door the fire bars of the grate can, from time to time, be freed of accumulations of ash which will greatly promote proper working conditions 20 in the stove.

But in order to fully understand the invention reference is made to the accompanying drawings, in which—

Figure 1 is a front sectional elevation 25 of the stove, and

Figure 2 a side sectional elevation on the line A—B, Figure 1, through the fire box.

Figure 3 is a front elevation of the stove.

Figure 4 is an end sectional elevation 30 through the oven on line C—D, Figure 3, and

Figure 5 shows in detail sectional plan 35 the operation of the vertical flue scraper.

The stove is provided with the usual oven and a fire box and the oven flues 6. The stove is constructed with a horizontal top flue leading over the oven from the fire box and a vertical flue down one side of the oven in each of which the self-acting scrapers 40 are provided. The third flue, or that below the oven and leading to the uptake, is filled with a tray, hereinafter described and which, on being withdrawn, will remove much of the dirt from below the oven. The door 7 45 of the oven is adapted to slide horizontally between guides 8 on the stove, the fire box door 9 being similarly adapted to sideways slide, away from the oven.

The door 7 is connected through the wall 50 of the roof flue to a framework 10 that is loosely fitted to the flue and which, when the door 7 is moved to the open position, will be slid along the flue in brushing contact with the stove top and the top of the oven.

55 The frame 10 can be made of brazed plates

which, when heated, will nicely fit the flue and its movement therein will scrape off accumulated soot and push it over into the vertical flue down which it will fall into a tray 11. In the end of said tray under the 60 vertical flue is a pivotally mounted deflector plate 12 operable from outside the stove through the wheel 13, and which assists to send the soot and dirt into the tray where it will be moved on and distributed by the 65 flue draught. This tray is provided medially with a baffle plate 14 the length of which is about one half the tray depth and which serves to turn the hot gases around to contact with the oven beyond the baffle, before 70 passing to the uptake flue 6a. This tray is, further, so constructed as to occupy the flue below the oven and has means which, when the tray is withdrawn, will scrape soot from the oven bottom.

75 In the side flue is a second scraping frame 15 on which is a spindle mounting a freely moving roller 16, the spindle being adapted to move vertically with the roller in a slot 17 in the flue wall. Connected to the oven 80 door is an upwardly curving bow 18 on which the roller 16 rests and which, as the door is opened, moves with it against the roller, thereby raising it and with it the frame 15. This frame, like the member 10, 85 is made to fit nicely in the flue when hot, without jamming, and its movement therein will brush off accumulations of soot and dirt that will fall into the tray 11, assisted by the deflector 12. This latter may also be 90 used as a damper to throttle the fire draught, when desired, for which purpose the part mounting the wheel 13 can be calibrated to indicate its position within the flue. The plate 12 is mounted in the tray 11 and extends from front to rear of same, thus closing the down flue when shut. A plate 19 is 95 between the roller 16 and the slot 17, to cover the slot as the roller moves therein.

100 Referring to the fire box and Figure 2 the fire bars 20 are arranged across the box from side to side. Under the bars is a front to rear plate 21 that is attached to the furnace door 9 and on which are scraping points 22 that come between the bars 20. 105 These move with the opening door and serve to disturb the ashes between the bars, which fall into the ash pan 23 that is removed in the ordinary way. An air damping device 24 is on the front of the ash pan for regu- 110

lating the draught. The doors 7 and 9 are provided with handles or grips, while in general appearance the stove will resemble those now in use.

5 Thus, by means of the invention, the working flues of a cooking stove can be kept clean by the opening and closing of the oven door, and the dirt removed in the tray 11 from time to time, while the grate bars of the

10 fire box are likewise freed of accumulations of ash by the simple movement of sliding open the furnace door.

Having now described my invention what I claim as new and desire to secure by Letters Patent is:—

1. In a stove in combination, a sideways sliding door to the oven, framelike scrapers so connected to the door as to be actuated thereby to slide along the horizontal top flue

20 and a vertical flue when the door is opened and a removable tray below the oven occupying the lower horizontal flue.

2. In a stove in combination, a sideways sliding door to the oven, framelike scrapers so connected to the door as to be actuated thereby to slide along the top and side flues when the door is opened, a removable tray below the oven and a medial baffle plate reaching from the back towards the front of

30 the tray and beyond which is the stove uptake flue.

3. In a stove in combination, a sideways sliding door to the oven, framelike scrapers so connected to the door as to be actuated thereby to be slid along the top and side flues when the door is opened, a removable tray below the oven in the lowest flue, a baffle in the tray and an adjustable deflector plate in the end of the tray immediately under the side flue.

4. In a stove in combination, a sideways sliding door to the oven, a framelike scraper connected to the sliding door in the topmost flue, a scraper in the vertical flue, a spindle thereon and a freely running wheel on the spindle, a slot in the flue wall through which the spindle projects and an upwardly curving bow on the oven door that engages and raises the wheel and scraper as the door slides open.

5. In a stove having a sliding door to the oven, vertical and horizontal scrapers in the flues so connected to the door as to be actuated thereby to slide therein when the oven door is opened and a tray in the flue below the oven, the combination with said parts of a fire box, a sliding door to the same, a plate attached to the door and upwardly tending teeth on said plate adapted to come between the fire bars of the box, as herein described.

In testimony whereof I affix my signature.

ALFRED MUNRO COURTNEY PRATT.
